Specification for Design.

Patented June 17, 1919.

Application filed April 8, 1919. Serial No. 288,649. Term of patent 3½ years.

To all whom it may concern:

Be it known that I, WILLIAM G. REITH, a citizen of the United States, residing at New York, in the county of New York and State of New York, have invented a new, original, and ornamental Design for Printed Silk, of which the following is a specification, reference being had therein to the accompanying drawings.

The figure is a plan view of a piece of printed silk showing my new design.

I claim:

The ornamental design for printed silk, as shown.

In testimony whereof I hereunto affix my signature.

WILLIAM G. REITH.
